UNITED STATES PATENT OFFICE.

ADOLPH T. JOHANSON, OF BENTON HARBOR, MICHIGAN, ASSIGNOR OF ONE-HALF TO
HARRY V. TUTTON, OF BENTON HARBOR, MICHIGAN.

WATER HEATER.

Application filed June 21, 1926. Serial No. 117,445.

My invention pertains to water-heaters in association with furnaces or boilers, and aims to provide a simple and efficient structure which may or may not be used, as desired, and without in any way interfering with the usual and proper functions of such furnace or boiler.

A further purpose of the invention is the production of a structure of this character 10 wherein the water tubes for the heater may be cleaned with facility and dispatch, and without disturbing other material or substantial parts of the appliance.

To enable those skilled in this art to have 15 a full and complete understanding of this invention, both from structural and functional standpoints, in the accompanying drawings, forming a part of this specification and throughout the several views of 20 which like reference characters have been employed to designate the same parts, a present desirable and preferred embodiment of the invention has been illustrated.

In these drawings, 25 Figure 1 is a front or side elevation of the improved structure with parts broken away to more clearly show the internal construction;

Figure 2 is an end elevation of the 30 appliance with some members shown in section;

Figure 3 is an enlarged fragmentary view 35 of a part of the appliance showing one of the detachable connectors for operably joining together the ends of adjacent pipes or tubes; and

Figure 4 is a vertical section on line 4—4 of Figure 3.

Referring to these drawings, it will be 40 perceived that the boiler has an outer, sheet-metal shell 11 and a corresponding inner, sheet-metal wall 12 spaced inwardly away therefrom a suitable distance to provide side and end water-legs 13 and 14, and the top space or compartment 15.

Such end legs are connected together by 45 a plurality of staggered, horizontal water-pipes 16, which are equipped with a lower, horizontal baffle-wall 17 just above the lowermost row of pipes on which it rests; such gas-deflecting wall beginning at the 50 left-hand vertical wall of the boiler, as shown in Figure 1, but terminating short of the opposite end wall to provide the space 18 for the upward flow therethrough of the 55 heated gaseous products of combustion.

Similarly an upper baffle-wall 19 rests on the topmost row of such pipes or tubes extending fully to the right-hand vertical wall of the boiler, but having a corresponding gap or passage 21 at the left-hand portion 60 of the structure, whereby the heated gases are compelled to traverse a tortuous path with respect to such water-pipes, the contents of which are heated thereby.

In the lower portion of the furnace or 65 boiler, a transverse, hollow, upright water-wall 22 connects together the two side-walls, their interiors being in communication and hence providing for the proper and efficient flow of the water therein, such wall 22 dividing 70 that portion of the boiler into two chambers, one of which is equipped with any approved form of liquid or gaseous fuel-burner 23, while the other is fitted with a grate 24 and suitable doors 25, 26 and 27, in the 75 front or side wall associated therewith.

This grate may be used to burn fuel on, or it may be employed for the drying and incineration of garbage or the like.

At one end the furnace or boiler is fitted 80 with a connection 28 adapted to be joined in the usual way with a stack or chimney for the discharge of the gases.

As will be readily understood, the efficient 85 and satisfactory oil or gas burner 23 has the grate 24 adjacent to it and which may be used to support the garbage or other refuse while it is being dried out by the heat generated at such contiguous or adjoining burner and on which it may be consumed 90 after it has been sufficiently freed from moisture in this manner.

Such grate may, at times, if desired, be employed for the burning of coal, coke, wood or other fuel, to supplement or augment the 95 heating action of the adjacent fluid-burner, or as a substitute therefor if required.

If preferred, the liquid or gas fuel-burner, may be of such capacity as to provide 100 adequate heat under all circumstances, or it may be of lesser size or power and supplemented in its heating function under extreme or unusual conditions, as by weather of very low temperature, by the combustion of fuel on the nearby auxiliary grate, whereby the heating surfaces of the appliance under such circumstances are subjected to the joint action of both heating means. Or, if wanted, as for instance, if it were temporarily impossible to secure fuel for the 110

fluid burner, the grate may be used alone for sustaining the solid fuel undergoing combustion.

The two heating means are so located and 5 the baffle-walls are so arranged that substantially the entire heating surfaces of the appliance are subjected to the action of the heat generated by each.

So far as this portion of the structure is 10 concerned, it is aimed to provide a construction which is simple in character, which operates efficiently, and which needs little attention, which is unlikely to become injured or damaged in ordinary service, and which 15 may be manufactured economically.

The water-heater associated with this boiler or furnace comprises a plurality of horizontal water-pipes 31—31, located in the water space or water jacket in the division- 20 wall 22, and extended through the water-spaces in the side legs of the boiler, and their metal walls, such pipes being expanded in the usual way to fit their holes in the inner and outer casings in fluid-tight manner.

Hence the water in these pipes has no 25 direct connection with that in the legs of the furnace, or that in the cross division-wall.

The water to be heated, as distinguished 30 from that in the boiler, is admitted to these pipes through a suitable manifold 32, secured against the outer face of the boiler in liquid-tight manner, in any approved way, and the water is fed into such manifold 35 through an admission or inlet pipe 33 preferably equipped with a control valve 34.

At the opposite end of the boiler, the other 40 ends of these pipes are connected together in like parallel relation by a manifold 35, and hence, it will be seen that these pipes, three in number, in the present instance, are connected together in multiple.

A series or horizontal row of water-pipes 36 extend through the water in the lower 45 portion of the top space 15 of the boiler, and through apertures in its sheet-metal end-walls, being expanded or enlarged in the latter to form tight fits, as is customary.

These pipes are joined together in series 50 relation, rather than in parallel or multiple manner, and, to this end, the manifold 35 is connected by a pipe 37 to a connection 38 bolted against the outer face or wall of the boiler, with a suitably interposed gasket, in 55 register with one end of the outermost pipe of the series, by means of stud bolts 39 bolted in the metal wall and accommodated in apertures of lugs 41 outstanding from the connection, nuts being used on such studs, 60 as is common practice, to hold the connection in position in liquid-tight association with such wall by reason of the interposed gasket.

The opposite end of the same pipe is 65 joined to the adjacent end of the next pipe

by a hollow fitting 42 similar to that designated 38, but large enough to cover the ends of two adjoining pipes.

By means of such fittings which are held 70 in place by similar studs and nuts with intervening gaskets, all of these upper pipes are joined together in series or serpentine relation, and the last pipe thereof is connected in similar manner to a discharge pipe 43 by means of which the hot water is conveyed to 75 the place where it is to be used.

Thus the water entering through the pipe 33 leaves by means of pipe 43, having been 80 suitably heated during its traverse through the pipe connections in the lower and upper portions of the boiler and all of which are immersed in and surrounded by different portions of the main body of water in such boiler.

This piping arrangement for the hot 85 water provides means for the quick distribution thereof through the parts of the boiler through which it flows and it hence reduces the strain to which the boiler is likely to be subjected by reason of uneven heating of the 90 members involved.

One advantage of this construction resides 95 in the fact, that, if such hot water-heater is not desired to be placed in service, then the pipes 31 and 36 forming parts thereof and originally installed in the boiler when manufactured, are not connected up for use and no harm results.

Furthermore, all of these hot water-heater 100 pipes or tubes are readily accessible for cleaning by merely removing the exterior manifolds or connections which give easy access to the full lengths of all of the pipes, such members being readily removable and replaceable, as will be understood.

This invention is not limited and restricted 105 to the precise and exact details of structure illustrated and described and may be incorporated in physical form in several different ways, all involving the principles of the invention; or stated otherwise, many mechanical changes may be made in the structure set forth without departure from the heart and essence of the invention, and without the sacrifice of any of its material benefits and 110 advantages.

I claim:

1. The combination of a boiler having outer walls and adapted to contain a body of water, said boiler in its lower portion having two combustion chambers separated from one another by a hollow wall adapted to contain water, a lower pipe extended through the water of said hollow wall, upper pipes 115 extended through said first mentioned body of water and through the opposite walls of the boiler, means outside of said walls connecting said upper pipes together, means connecting said lower pipe to said upper pipes, and means to feed water to said lower

pipe, whereby the water may be heated in flowing through said lower pipe and upper pipes.

2. The combination of a boiler having outer walls and adapted to contain a body of water, said boiler in its lower portion having two combustion chambers separated from one another by a hollow wall adapted to contain water, a plurality of lower pipes connected together in multiple relation and extended through the water of said hollow wall, upper pipes extended through said first

mentioned body of water and through the opposite walls of the boiler, means outside of said walls connecting said upper pipes together in series relation, means connecting said lower pipes to said upper pipes, and means to feed water to said lower pipes, whereby the water may be heated in flowing through said lower and upper pipes. 15 20

In witness whereof I have hereunto set my hand.

ADOLPH T. JOHANSON.
